US0D1054385S

(12) **United States Design Patent** (10) **Patent No.:** **US D1,054,385 S**
(45) **Date of Patent:** **** Dec. 17, 2024**

(54) **CHARGING CONNECTOR**

(71) Applicant: **Schumacher Electric Corporation**,
Fort Worth, TX (US)

(72) Inventors: **John S. Whiting**, North Richland Hills,
TX (US); **Randall Lawson**,
Champaign, IL (US); **Patrick J. Clarke**, St. Charles, IL (US); **Donald Anderson**, Oak Park, IL (US); **Mark Kurth**, La Porte, IN (US);
Oluwadurotimi Solola, Chicago, IL (US); **John C. Olson**, Livingston, TX (US)

(73) Assignee: **Schumacher Electric Corporation**,
Fort Worth, TX (US)

(**) Term: **15 Years**

(21) Appl. No.: **29/786,615**

(22) Filed: **Jun. 1, 2021**

(51) LOC (14) Cl. **13-03**
(52) U.S. Cl.
USPC **D13/146**

(57) **CLAIM**

The ornamental design for a charging connector, as shown and described.

DESCRIPTION

FIG. 1 is a first perspective view of a charging connector, shown in an environment of use;

FIG. 2 is a second perspective view of the charging connector;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The broken lines in the drawings illustrate both portions of the article and environmental subject matter that form no part of the claimed design.

1 Claim, 7 Drawing Sheets
